UNITED STATES PATENT OFFICE.

CHARLES H. DUFFY, OF NEW YORK, N. Y., ASSIGNOR TO THE AUTOMATIC TARGET MACHINE COMPANY, A CORPORATION OF NEW YORK.

TARGET APPARATUS.

No. 824,982.

Specification of Letters Patent.

Patented July 3, 1906.

Application filed June 16, 1905. Serial No. 265,614.

To all whom it may concern:

Be it known that I, CHARLES H. DUFFY, a citizen of the United States, residing in the city, county, and State of New York, have 5 invented certain new and useful Improvements in Target Apparatuses, of which the following is a specification.

This invention relates to target apparatuses such as are employed in connection 10 with simulated guns, pistols, or other firearms. In some of these devices, it may be explained, the indicator at the target showing the point aimed at by the marksman is controlled electrically and appears at the 15 point on the target to which the aim is directed when the marksman closes the circuit by pulling the trigger. Such a target apparatus will be found fully described in the patents to McCullough, No. 679,325, of July 30, 20 1901, and No. 707,617, of August 26, 1902. In some other of these devices no electricity is employed, the indicator being controlled and moved about mechanically over the target-field by the act of aiming the simulated 25 gun or pistol. The patent to McCullough, No. 768,536, of August 4, 1904, shows an apparatus of this character.

The object of the present invention is to provide a target apparatus wherein when the 30 simulated firearm is aimed and the trigger pulled an illuminated indicator or indicating-spot will appear on the target at the point aimed at by the marksman.

In the accompanying drawings, which 35 serve to illustrate embodiments of the invention, Figures 1 to 8 illustrate the application of the invention to a target apparatus in other respects similar to that shown in the before-mentioned patent, No. 679,325. Fig. 40 1 is a general and somewhat diagrammatic side view, on a relatively small scale, of the entire apparatus. Fig. 2 is a plan of the contact-disk. Fig. 3 is a section of said disk and shows also the common contact point or terminal. Fig. 4 is a face view of the target-box with a part of the target broken away. Fig. 5 is a rear view of the target-box. Fig. 6 is an inside view of the target-box from the front, showing the circuit-wires. Fig. 7 is a 45 view showing the inner face of the target and form of illuminated spot. Fig. 8 is a transverse section of the box taken at line x^8 in Fig. 4.

It will only be necessary to describe the

general features briefly, as they are fully 55 illustrated and described in the before-mentioned patent, No. 679,325.

1 is a simulated firearm mounted universally on a stand 2, and 3 is the target-box, mounted also on a stand 4 at a fixed distance 60 from the firearm 1. Below the firearm in the stand is mounted a contact-disk 5, (seen in Figs. 2 and 3,) said disk, as here shown, being similar in contour and in its divisions to the target. As seen in Fig. 2, it has a 65 bull's-eye contact C and eight segment-contacts S. Above this disk 5 is a terminal contact T, which is connected with the firearm 1 and moves about over the disk as the line of aim of the firearm moves about over the target in aiming. When the trigger of the firearm is pulled, the terminal T falls and by contact with some segment of the disk 5 closes an electric circuit through one of the 70 eight circuit-wires W and return-wire W', 75 supplied by the battery B. All of the above features are shown in the patents, Nos. 679,325 and 707,617, before mentioned. According to the present invention each segment or part C and S of the disk 5 forms a 80 terminal of a circuit through an incandescent lamp at the target corresponding in position with the position of the segment in the disk. For example, the bull's-eye contact C is a 85 terminal of a circuit through a lamp at the bull's-eye of the target.

The target and the novel features pertaining to it are illustrated in Figs. 4 to 8. In these figures, 6 is the target in the front of the box 3. It may be of translucent or ground 90 glass with an outer zone, (marked 3,) an inner zone, (marked 4,) and a bull's-eye, (marked 5,) Fig. 4. Within the target-box 3, back of the target, are mounted nine incandescent lamps 7—four for the segments of the outer zone, four 95 for the segments of the inner zone, and one for the bull's-eye. As stated, each of these lamps is in circuit with one of the wires W and all are in circuit with the return-wire W' and the terminal T. Fig. 6 shows the connecting-wires in the box, and Figs. 5 and 8 show the binding-posts 8 at the back of the target-box. This is a mere matter of electric-light wiring and can be done by any electrician. Fig. 8 shows the screens about the 105 several lamps for concentrating the light on one spot on the target. This device, as herein shown, consists of a thin metal plate 9 at

the back of the target having in it holes, one for each lamp. Projecting inward from this plate at the several holes and housing the respective lamps are tubular screens 10. These 5 screens will be, by preference, of polished metal and will aid in concentrating a round spot of light on the target when the lamp is lighted by the closure of the circuit through it.

As herein shown there is a disk 9^a of opaque 10 material between the plate 9 and the target, Figs. 7 and 8, provided with holes or apertures corresponding in position to the lamps 7 and to the holes in the plate 9, and on the back of the translucent target, Fig. 7, are painted 15 round black spots 9^b. With this construction the indicator will be a bright ring of light encircling a black spot—that is, this is what the marksman will see through the translucent target when he pulls the trigger of the 20 aimed firearm.

As here shown the zone on the target is divided into four segments, and there is one lamp only for each segment, so that if the marksman aims at any point in such segment 25 this lamp will be lighted. The bull's-eye lamp may be of red glass, for example, or the glass of the target at the bull's-eye may be stained red. These are details to which the invention is not limited.

30 In the target device or apparatus shown in the Patent No. 679,325 before mentioned, there is a device for automatically breaking the circuit closed by pulling the trigger after the indicator has been displayed at the target 35 for a few seconds, and the same or a similar device will be employed in the present apparatus for automatically breaking the circuit through the lamp at the target. This device is now well known, and it has not been deemed 40 necessary to illustrate it herein.

Obviously the invention can be applied to a mechanically-operated apparatus similar to that shown in the said Patent No. 738,536 by 45 producing an illuminated spot on the target in lieu of a black spot, the circuit through the lamp employed being completed by pulling the trigger of the firearm, as above described.

In the description of the invention herein 50 shown it will be noted that the device which is universally mounted and which is aimed by the marksman has been called a "firearm," or "simulated firearm," but it must be understood that this device may be of any kind that 55 can be aimed and which has a trigger or its equivalent. In this class of target apparatus the "firearm," so called, is usually made to

simulate a gun or pistol. It should be noted also that any selecting means or means whereby the aiming of the firearm determines the 60 point on the target where the illumination is to appear may be employed, and the same may be said as to the means controlled by the trigger for effecting such illumination of the target.

Having thus described my invention, I 65 claim—

1. A target apparatus, having a universally-mounted firearm, a target sufficiently translucent to permit light to pass through it, an incandescent lamp behind the target, for 70 illuminating a spot thereon, means controlled by the trigger of the firearm for completing an electric circuit through said lamp, the circuit and generator for supplying said lamp, and means, controlled by the movement of the 75 firearm in aiming, which determines the position of said illuminated spot on the target.

2. A target apparatus, having a universally-mounted firearm, a target sufficiently translucent to permit light to pass through it, 80 an incandescent lamp behind the target, for illuminating a spot thereon, means controlled by the trigger of the firearm for completing an electric circuit through said lamp, and the 85 circuit and generator for supplying said lamp.

3. A target apparatus, having a universally-mounted firearm, a target of translucent material, a plurality of incandescent lamps disposed behind said target, electric circuits including the respective lamps and a generator, means controlled by the movement of the 90 firearm in aiming, which selects one of said lamps, and means controlled by the trigger of the firearm, which closes the circuit through the lamp selected.

4. In a device for the purpose specified, the combination of a target 6 of translucent material, a plurality of incandescent lamps 7 behind said target, circuits through the respective lamps, said circuit including a generator, 100 tubular screens about the respective lamps and extending up to the target, a universally-mounted firearm adapted to be aimed at the target, and means, controlled by the operation of said firearm for selecting and completing 105 the circuits through the lamps.

In witness whereof I have hereunto signed my name, this 14th day of June, 1905, in the presence of two subscribing witnesses.

CHARLES H. DUFFY.
